(57) **CLAIM**

The ornamental design for a baby monitoring apparatus set as shown and described.

DESCRIPTION

FIG. 1 is a front, bottom, right perspective view of a monitor of a baby monitoring apparatus set showing my new design shown separately for ease of illustration;

FIG. 2 is a rear, top, left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, bottom, right perspective view of a camera of the baby monitoring apparatus set shown separately for ease of illustration;

FIG. 10 is a rear, top, left perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a front, bottom, right perspective view of the baby monitoring apparatus set;

FIG. 18 is an enlarged view of portion 18 shown in FIG. 15;

FIG. 19 is an enlarged view of portion 19 shown in FIG. 15;

FIG. 20 is an enlarged view of portion 20 shown in FIG. 15; and,

FIG. 21 is an enlarged view of portion 21 shown in FIG. 16. The dash-dash broken lines in the drawings depict portions of the baby monitoring apparatus set that form no part of the
